UNITED STATES PATENT OFFICE.

GIUSEPPE RESTUCCI, OF NAPLES, ITALY.

DEVICE FOR SUPERHEATING STEAM.

1,348,895.

Specification of Letters Patent. Patented Aug. 10, 1920.

Application filed September 28, 1918. Serial No. 256,031.

To all whom it may concern:

Be it known that I, GIUSEPPE RESTUCCI, a subject of the King of Italy, and residing at Naples, Italy, (whose post-office address is 5 156 Nuovo Corso Garibaldi,) have invented certain new and useful Improvements in Devices for Superheating Steam, of which the following is a specification.

This invention relates to a device for intensified thermic and dynamic superheating of steam. It is intended for superheating steam at the expense of the source of heat, and therefore it must be applied close to the automatic stop valve, preferably to the 10 boiler itself.

A construction according to this invention is illustrated by way of example in the accompanying drawing, in which:

Figure 1, is a vertical section of the valve 20 closed.

Fig. 2 is a vertical section of the valve partly open, and

Fig. 3 is a cross section on the line A B of Fig. 1 —a,— is the outer casing, —a'— a cylinder containing several series of nozzles 25 —d,—b— a piston for regulating the passage of steam from the boiler to the engine, —c— the screw used to regulate the travel of the piston in order to uncover the series of 30 nozzles, —i— a hand wheel keyed to the screw spindle —c— for moving the latter, —l— steam outlet opening from the boiler, —m— a pipe, —n— and —o— the two walls of the piston, —e— a circular cage constituted by a number of circular segment 35 blades between which steam passes on its way into the pipe —m— leading to the engine, —f— the indicator of the number of series of nozzles, —h— a small opening intended to balance the piston.

The cylindrical piston —b— which is a fairly tight fit in the cylinder —a'— opens or closes gradually small exhaust nozzles provided in the wall of said cylinder.

The cylinder —a'— is surrounded by steam from the boiler which steam is admitted at —l— and remains at the temperature of the boiler. The steam passing through the expanding nozzles, a small 45 quantity in each nozzle, is in contact with a comparatively large metal surface, the metal having another surface exposed at all times to the boiler steam, and consequently the metal surfaces are maintained at all times 50 at substantially the temperature of the boiler steam. Consequently the expanding

steam passing through the nozzles in contact with the hot metal takes up heat; and as the steam expands into the space between the nozzles *d* and blades *e*, the heat freed by 60 the expanding steam, which does no work in expanding, converts part of the water in the steam, if it is wet, into steam, or if it is dry steam, will superheat it.

At the end of the nozzles —*d*—, the steam, 65 with heat added thereto as described, is discharged against fixed blades —*e*— shaped so as to form conduits, in which it is compressed by centrifugal action and escapes into the pipe —*m*— through which it passes 70 into the engine after having overcome the pressure in the pipe —*m*—.

The pressure which is produced in the pipe —*m*— depends on two factors; exhaust and escape of the steam, which are both 75 variable at will, but in any case in the pipe —*m*— there is superheated steam. The object of the blades is to reduce slightly the speed of the steam and give it a centrifugal action. At the same time, in the zone comprised between the nozzles and the blades a 80 depression is produced which maintains constant the exhaust from the nozzles themselves.

With the device working at the maximum 85 power, there is obtained a fuel economy always greater than 30%—a very important point, more particularly in the present conditions owing to the insufficiency and high price of fuels generally.

Having now particularly described and ascertained the nature of my said invention, and in what manner the same is to be performed, I declare that what I claim is;

1. A device for superheating steam comprising expanding nozzles, means for supplying heat to the steam while expanding, and blades arranged to impart centrifugal action to the expanded steam. 95

2. A device for superheating steam comprising expanding nozzles maintained substantially at the original temperature of the steam and arranged angularly with respect to corresponding radii upon the circumference of a circle, and blades for imparting 100 centrifugal action to the expanded steam arranged on the circumference of a concentric circle.

3. A device for superheating steam comprising a hollow cylinder having a plurality 110 of openings in its walls, means for leading steam to the exterior of said cylinder, a hol-

low cylindrical piston reciprocable within said cylinder, and a plurality of blades mounted within said cylinder disposed interiorly of said piston.

5. 4. In a device for superheating steam the combination comprising a plurality of expanding nozzles located about an axis, a plurality of blades for imparting centrifugal action to the expanded steam disposed 10 centric to the same axis, and a valve arranged to close the space between said nozzles and blades.

5. In a device for superheating steam, the combination comprising a hollow cylinder 15 having a plurality of openings in its walls, a plurality of blades arranged longitudinally within said cylinder concentrically about the axis thereof, and a valve arranged for closing the space between said cylinder 20 and blades.

6. In a device for superheating steam, the combination comprising a hollow cylinder having a plurality of openings in its walls,

a plurality of blades arranged longitudinally within said cylinder concentrically about the axis thereof, and a hollow cylindrical valve reciprocable within said cylinder and arranged for closing the space between said cylinder and blades. 25

7. In a device for superheating steam, the 30 combination comprising a hollow cylinder having a plurality of openings in its walls, a plurality of blades arranged longitudinally within said cylinder concentrically about the axis thereof, and a hollow cylindrical valve reciprocable within said cylinder and arranged to close the space between said cylinder and blades, said valve having 35 a guiding projection extending interiorly of 40 said blades.

In testimony whereof I hereunto sign my name in the presence of two witnesses.

GIUSEPPE RESTUCCI.
